(57) **CLAIM**

The ornamental design for a feeder bottle, as shown and described.

DESCRIPTION

FIG. 1 is a top, front, left perspective view of a feeder bottle, shown exploded for clarity of disclosure;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is a bottom, rear, right perspective view of FIG. 1, shown assembled for clarity of disclosure.

In the drawings, the equal-length broken lines depict portions of the feeder bottle that form no part of the claimed design.

1 Claim, 8 Drawing Sheets
